C. F. BUENTE

SERVICE CONNECTION FOR CONCRETE MAINS

Filed July 21, 1919

WITNESS

R. A. Balderson

INVENTOR.

Charles F. Buente
by Baker, Byrne & Lamb
his Atty.

UNITED STATES PATENT OFFICE.

CHARLES F. BUENTE, OF AVALON, PENNSYLVANIA.

SERVICE CONNECTION FOR CONCRETE MAINS.

Application filed July 21, 1919. Serial No. 312,181.

To all whom it may concern:

Be it known that I, CHARLES F. BUENTE, a citizen of the United States, and residing at Avalon, in the county of Allegheny and 5 State of Pennsylvania, have invented a new and useful Improvement in Service Connections for Concrete Mains, of which the following is a full, clear, and exact description, reference being had to the accompanying 10 drawings, forming part of this specification.

The present invention relates broadly to service connections for mains, and more particularly to a connection of this type for 15 mains constructed of concrete or like material.

The principal object of the present invention is to provide a service connection which may be imbedded at any desired point or 20 points in a main at the time the main is cast or molded, so as to be available for use as desired.

Another object of this invention is to provide a connection of this type having means 25 for protecting the interior thereof from mutilation or accumulations of foreign matter when not in use.

Still another object of the present invention is to provide a service connection having 30 means for controlling the flow therethrough to permit house connections or the like to be made therewith under the most favorable conditions.

A still further object of the invention is 35 to construct a service connection having a longitudinal axis considerably longer than the transverse axis to successfully resist turning forces tending to loosen the connection with respect to the material in which it is supported or imbedded.

The foregoing and other objects, together 40 with their attendant advantages, will be better understood by reference to the accompanying specification and drawings forming a part thereof, it being premised that changes may be made in the preferred form illustrated within the scope of the appended claims, without departing from the spirit of the invention.

50 Figure 1 is a cross sectional view through a portion of a main containing my improved service connection showing the same connected for use;

Figure 2 is a longitudinal sectional view through my improved service connection; 55

Figure 3 is a cross sectional view on the line III—III of Figure 2; and

Figure 4 is a top plan view of service connection.

Referring more particularly to the drawings, I have illustrated a concrete main or conduit 10 which may be suitably reinforced by members 11. At the time the main or conduit is formed my improved service connection may be molded therein. 60 In the form illustrated this connection comprises a main body 12, generally oval or rectangular in cross section to provide a longitudinal axis of greater length than the transverse axis. By reason of this construction it will be apparent that it is impossible to turn the connection with respect to the body of the main and thereby loosen the 65 same.

The body 12 may also be provided with 70 upper and lower flanges 14 assisting in maintaining the connection securely in position.

Extending through the body of the connection is a threaded opening 15 having a 75 valve seat 16 formed adjacent the lower 80 end thereof. The valve seat 16 may be formed by terminating the threads short of the inner end of the connection, or by contracting the opening as found desirable. Intersecting the opening 15 is a curved outlet 85 17 adapted when in use to receive a service pipe 18, and when not in use the outlet is normally closed by a plug 19 screw-threaded 90 therein and lying flush with the upper surface of the body 12. The plug 19 may be 95 suitably provided with an opening 20 for the reception of a wrench for removing the plug when it is desired to make a house connection.

A second plug 21 corresponding to the 95 plug 19 may be employed for closing the opening 15. It will be apparent that these plugs 15 prevent mutilation of the threads in the connection and prevent the accumulation of foreign matter therein.

Screw-threaded in the opening 15 is a 100 plug valve 22 adapted to seat on the seat 16 and close the outlet 17 when the device is not connected to a service line. Due to this construction, when it is desired to connect 105 the outlet 17, the plug 19 may be removed

and a suitable pipe 18 inserted. After the joints have been rendered tight, the plug 21 may be removed and the valve 22 raised to the position indicated in Figure 1. By 5 lowering the valve 22 the supply of water through the service pipe 18 may be regulated or cut off at will so that repairs may be made as found necessary.

The body of the connection may be 10 constructed of any suitable material and may have any configuration adapting the same for the particular main with which it is used.

I claim:

15 1. A service connection comprising a body member having a plurality of openings formed in the outer face thereof, and a single opening formed in the inner face thereof and aligning with one of said openings in the outer face, said openings intersecting within the body member, and a single means for closing one or all of said openings, one of said openings being threaded throughout a sufficient portion of its length 20 to permit said means to be moved to a position entirely within said body member, substantially as described.

2. A service connection comprising an elongated body member having a plurality 30 of openings formed in the outer face thereof, and a single opening formed in the inner face thereof, said openings intersecting within said body member, and a single means for closing one or all of said openings, one of said openings being threaded throughout a sufficient portion of its length 35 to permit said means to be moved to a position entirely within said body member, substantially as described.

40 3. A main section having entirely imbedded therein a service connection the faces of which are substantially flush with the surfaces of the main, said connection having a plurality of openings formed in the outer 45 face thereof, and a single opening formed in the inner face thereof, said openings intersecting within the body of the connection, and a single means for closing one or all of said openings, substantially as described.

45 4. A main section having imbedded therein an elongated service connection with the faces of the connection substantially flush with the surfaces of the main, said connection having a plurality of openings formed 55 in the outer face thereof, and a single opening formed in the inner face thereof, said openings intersecting within the body of the connection, and means for closing said 60 openings, substantially as described.

5. A main section having imbedded therein an elongated flanged service connection with the faces of the connection substantially flush with the surfaces of the main, said connection having a plurality of open-

ings formed in the outer face thereof, and a single opening formed in the inner face thereof, said openings intersecting within the body of the connection, and means for closing said openings, substantially as described. 70

6. A service connection adapted to be imbedded in composition mains, comprising a body member having an opening extending therethrough for communication directly 75 with the interior of the main, an outlet opening intersecting said first mentioned opening intermediate the ends thereof, said openings extending substantially parallel throughout a portion of their lengths, and a valve adapted to close both of said openings at the point of intersection when the connection is not in use, said valve being adapted to close one end of said first mentioned opening when the connection is in 80 use, substantially as described.

7. A service connection adapted to be entirely imbedded in composition mains, comprising a body member having an opening extending therethrough for communication directly with the interior of the main, an outlet opening intersecting said opening intermediate the ends thereof, said openings extending substantially parallel throughout a portion of their lengths, and a valve adapted 90 to close both of said openings at the point of intersection when the connection is not in use, substantially as described.

8. A device of the class described for facilitating service connections with mains, comprising a flanged body member adapted to be imbedded in a main and having intersecting openings formed therein, one of said openings being adapted to receive the service connection, and a valve adapted to close both of said openings when the connection is not in use, substantially as described. 100

9. As an article of manufacture, a service connection for composition mains, comprising an elongated body member adapted to 110 be imbedded in a main and having openings formed therein, said openings extending substantially parallel throughout a portion of their lengths and then intersecting to form a single opening, and a single valve 115 adapted to close one or both of said openings, substantially as described.

10. As an article of manufacture, a service connection for composition mains comprising a body member adapted to be imbedded in a main and having an opening extending therethrough and having an outlet intersecting said opening intermediate the ends thereof, said outlet extending substantially parallel with said opening throughout a portion of its length, and a valve longitudinally adjustable in said opening for controlling said outlet, substantially as described. 120

11. A service connection for composition 125

- 5 mains comprising a body member adapted to be imbedded in a main and having an opening extending therethrough and having an outlet intersecting said opening intermediate the ends thereof, said outlet extending substantially parallel with said opening throughout a portion of its length, a valve longitudinally adjustable in said opening for controlling said outlet, and means for closing the ends of said opening and said outlet, substantially as described.
- 10 12. A service connection adapted to be imbedded in a main, comprising an elongated flanged body member having intersecting openings formed therein, said elongation being in a direction at right angles to the axis of said openings, and a valve adapted
- 15 to close both of said openings when a connection is not in use, substantially as described.
- 20 13. A service connection for composition mains comprising a body member adapted to be imbedded in a main and having a threaded opening extending therethrough, and having a threaded outlet intersecting said opening, said outlet extending substantially parallel to said opening throughout a portion of its length, and a screw threaded valve longitudinally adjustable in said opening for controlling said outlet, substantially as described.
- 25
- 30
- 35 In testimony whereof, I have hereunto set my hand.

CHARLES F. BUENTE.
